CLAIM

The ornamental design for a collapsible container, as shown and described.

DESCRIPTION

FIG. 1 is a perspective view of a collapsible container showing my new design;

FIG. 2 is a top plan view thereof;

FIG. 3 is a front elevational view thereof;

FIG. 4 is a bottom plan view thereof;

FIG. 5 is a perspective view thereof; in collapsed position;

FIG. 6 is a front elevational view of FIG. 5;

FIG. 7 is a front elevational view of a second embodiment in FIG. 1;

FIG. 8 is a bottom plan view of FIG. 7; and,

FIG. 9 is a front elevational view of FIG. 7, in collapsed position.

The top of FIG. 7 embodiment is identical to that of the first embodiment, as shown in FIG. 2.
